UNITED STATES PATENT OFFICE.

WILLIAM W. STRATTON AND ADAM STEUERWALD, OF COLUMBUS, OHIO, AS
SIGNORS OF ONE-THIRD TO WILLIAM WALTER ZAPP, OF SAME PLACE.

ADJUSTABLE CORNICE.

SPECIFICATION forming part of Letters Patent No. 234,344, dated November 9, 1880.

Application filed August 10, 1880. (No model.)

To all whom it may concern:

Be it known that we, WILLIAM W. STRATTON and ADAM STEUERWALD, of Columbus, in the county of Franklin and State of Ohio, 5 have invented a new and Improved Adjustable Cornice, of which the following is a specification.

The object of our invention is to provide a new and improved cornice for curtains and 10 lambrequins, which can be adjusted to suit any desired opening or space, such as a window, door, niche, and the like, and is simple in construction and convenient in use.

The invention consists in a cornice formed 15 of a center-piece and two extension-pieces sliding in a recess in the back of the center-piece, and locked in any desired position by means of a pinion and a key attached to the center-piece, the pinion engaging with racks 20 attached to the extension-pieces.

In the accompanying drawings, Figure 1 is a rear elevation of our improved adjustable window-cornice. Fig. 2 is a plan view of the same. Fig. 3 is a cross-sectional elevation of 25 the same on the line *x x*, Fig. 1. Fig. 4 is a cross-sectional elevation of the same on the line *y y*, Fig. 1.

Similar letters of reference indicate corresponding parts.

30 A center-piece, A, which may be ornamented in any suitable manner, if desired, is recessed on its rear side, so as to receive the sliding extension-pieces B B, having end pieces, C C, hinged thereto, which end pieces may be braced 35 by means of a hook, D, or any other suitable brace. The sliding extension-pieces B B are held to the center-piece A by the springs E E, attached to the upper edge of the rear side of the center-piece A, and pressing against the 40 said sliding extension-pieces, as shown, thus leaving a clear and unobstructed lower edge of center and extension pieces for attaching a curtain or lambrequin.

A pinion, F, and a nut, G, provided with a

handle, H, are loosely mounted on a threaded 45 pin, K, in the middle of the rear side of the center-piece A, and racks J J, engaging with the pinion F, are attached to each extension-piece B.

If one extension is drawn in or out a certain distance, the other extension-piece moves the same distance, whereby the middle of the center-piece always forms the middle of the entire bracket. The extensions having been drawn in or out a certain distance, they are 55 locked in the desired position by turning down the nut G by means of the handle H. The pinion is thus prevented from rotating, and thereby prevents a movement of the extension-pieces. The inner ends of the extension-pieces 60 are recessed on a curved line to fit closely against the pinion F.

We are aware that the sliding side pieces have been adjusted by a right-and-left screw, 65 which is affected by the weather, and cannot be taken apart without taking out the locking-screws, while our three pieces can be separated without even loosening a screw.

We are also aware that the sliding pieces have been provided with hinged pieces near 70 the ends, while ours are at the ends, and when closed form one solid line and finished end on cornice.

What we claim as new and of our invention 75 is—

A cornice whose sliding and center pieces are locked by a pinion and key on the center-piece, and racks on the extension-pieces, as shown and described, whereby the pieces may be drawn apart without loosening a screw, and 80 when closed form an unbroken line and finished end.

WILLIAM WEBER STRATTON.
ADAM STEUERWALD.
